J. H. THORP.

GIMP.

No. 16,551.

Patented Feb. 23, 1886.

UNITED STATES PATENT OFFICE.

JAMES H. THORP, OF BROOKLYN, NEW YORK.

DESIGN FOR GIMP.

SPECIFICATION forming part of Design No. 16,551, dated February 23, 1886.

Application filed January 11, 1886. Serial No. 188,267. Term of patent 14 years.

To all whom it may concern:

Be it known that I, JAMES H. THORP, of Brooklyn, in the county of Kings and State of New York, have invented a new, useful, and original Design for Gimp, of which the following is a specification.

The accompanying photographic illustration represents a face view of my new design for gimp.

10 This invention relates to a new configuration of gimp and analogous fabrics.

The sides of the gimp consist of U-shaped figures *a a*, between which is a row of central oval figures, *b b*, that resemble rounded cushions.

15 Between every two figures *b b* is a line, *c*, which extends from the U-shaped figure *a* on one side of the gimp to a U-shaped figure *a* on the other side of the gimp. The diamond-shaped figures

d d appear on the rows of figures *a a* on each side of the row *b b* of central oval figures. 20

I claim—

1. The design for the new configuration of a gimp, the same consisting of the U-shaped figures *a a* at the sides, the central cushion-like oval figures, *b b*, and the lines *c* between the figures *b b*, substantially as shown. 25

2. The design for the new configuration of a gimp, the same consisting of the U-shaped figures *a a* and diamond-shaped figures *d d* at the sides, the central cushion-like oval figures, *b b*, and the lines *c* between the figures *b b*, substantially as shown. 30

JAMES H. THORP.
